UNITED STATES PATENT OFFICE

WILLIAM HANLEY, OF EAST ORANGE, NEW JERSEY, ASSIGNOR TO FERGUSON BROTHERS MANUFACTURING COMPANY, OF HOBOKEN, NEW JERSEY, A CORPORATION OF NEW JERSEY

SCREEN

Application filed September 15, 1927. Serial No. 219,720.

There has been for some time past a growing demand for elaborately decorated folding card tables, such tables being frequently very expensive. Consequently there has been 5 a disinclination on the part of the owners to store the tables when not in use, because of their attractiveness and because of the liability of their becoming damaged.

The object of this invention is to provide a 10 suitable holder for the table whereby it may be used as a screen when not in use as a card table, thus forming an attractive and useful article of furniture and giving to the table a double use.

15 My invention therefore comprises a screen which includes a folding card table as an element and more particularly comprises a holder and a folding card table removably secured thereto, to form a screen, said holder 20 having an upright member to which the table is removably secured, a lower cross member on which the lower side of the table rests and an upper cross member overlapping the upper side of the table.

25 A practical embodiment of my invention is represented in the accompanying drawings, in which

Fig. 1 represents a front view of the screen.

Fig. 2 represents a side view of the same.

30 Fig. 3 represents a back view of the screen.

Fig. 4 represents a top plan view of the holder.

Fig. 5 represents a front view of the same.

Fig. 6 represents a side view of the holder.

35 Fig. 7 represents a rear view of the same.

Fig. 8 represents an enlarged detail view showing the pivotal connection between the latch and the holder.

40 The folding card table 1 may be of any well known or suitable construction and its top may be suitably ornamented, as shown at 2.

45 The holder for the table is shown as including an upright member 3 to which the table is removably secured, a lower cross member 4 on which the lower side of the table is adapted to rest, and an upper cross member 5 adapted to overlap the upper side of the table. The lower cross member 4 may 50 be provided at its opposite ends with suit-

able legs 6 for supporting the holder and table when attached thereto. This lower cross member 4 may also be provided at its ends with stops 7 for positioning the lower side of the table on the said cross member. 55 These cross members may be made ornamental in character to add to the attractiveness of the screen.

The means which I have shown for removably securing the table to the holder is 60 constructed as follows:

Two of the frame pieces 8 which extend across the bottom of the table are shown as 65 provided with oppositely projecting hooks 9 arranged to receive the arms 10 of a spring pressed latch which is pivoted on the upright member 3 by means of a screw-threaded bolt 11 which passes through the said upright member. A coil spring 12 surrounds the screw-threaded bolt 11 between the latch and the inner face of the upright 3, tending to 70 yieldingly hold the latch at the limit of its movement away from the said upright member. A thumb nut 13 bears against the outer face of the upright and has a screw-threaded engagement with the outer end of the bolt 11 for adjusting the tension of the latch. The upper cross member 5 is preferably provided 75 with a handle 14 for use in carrying the screen from place to place.

When it is desired to secure the table to the holder to form a screen, the table is placed in position between the upper and lower cross members of the holder and the latch is swung into engagement with the hooks carried by 80 the table. Any liability of the table becoming unintentionally detached from its holder may be prevented by turning the thumb nut to increase the tension on the latch and thereby draw the table snugly to the holder. 85

It is evident that various changes may be resorted to in the construction, form and arrangement of the several parts without departing from the spirit and scope of my invention; hence, I do not wish to be limited 90 to the particular embodiment herein shown and described, but what I claim is:—

1. A holder adapted to removably support a folding card table to form a screen, and means for removably securing the table to the 95

holder comprising hooks on the bottom of the table and a latch mounted on the holder in position to be moved into and out of engagement with said hooks.

2. A holder adapted to removably support a folding card table to form a screen, and means for removably securing the table to the holder comprising hooks on the bottom of the table, a latch yieldingly mounted on the holder in position to be moved into and out of engagement with said hooks, and means for adjusting the tension of the latch.

3. A holder adapted to removably support a folding card table to form a screen, said holder comprising a lower cross member adapted to support the table, an upper cross member adapted to overlap the upper side of the table, a connecting upright member, and means thereon located between the upper and lower cross members for removably securing the table to the holder, said lower cross member having stops for positioning the lower side of the table and said upper cross member having a handle for use in carrying the screen from place to place.

25. In testimony, that I claim the foregoing as my invention, I have signed my name this 13 day of September, 1927.

WILLIAM HANLEY.
